MAGNETRON GENERATOR.

Karl Fritz, Berlin, Germany, assignor to Telefunken Gesellschaft für Drahtlose Telegraphie m. b. H., Berlin, Germany, a corporation of Germany

Application December 31, 1935, Serial No. 56,856
In Germany December 22, 1934

6 Claims. (Cl. 250—36)

The present invention relates to magnetron generators, and the methods of controlling the frequency thereof. It is among the objects of my invention to provide means in a magnetron discharge tube circuit such that high frequency oscillations may be controlled from an outside source, if desired, and such that these oscillations may be multiplied in an output circuit from said discharge tube.

10 It has been proposed separately to control by means of high frequency the voltage of magnetrons; furthermore it has been suggested to carry out the control by means of a circular high frequency magnetic field (high frequency current control).

In the method according to the invention there is utilized as separate control the relationship between the plate current I_e and the angle α between the resultant magnetic field and the axis 20 of the electrode system. There is hereby considered on the one hand the magnitude of the plate current and on the other hand, the current distribution on the plate segments. Two different modes of construction will be obtained but having common characteristic features, namely the separate control by utilizing the aforementioned angle relations. The magnitude of the plate current depends in a high degree upon the value of this angle. The method according to the invention 30 possesses various advantages. In the first place, the control energy is extremely low, and secondly the method is particularly well suited for frequency doubling and frequency multiplication.

The idea underlying the present invention 35 resides in effecting the separate control of the electrons by controlling their direction of flight. In order to do this the principal magnetic field of a magnetron is operated in one of the ordinary circuits and is superposed by a weak high frequency control field in a direction deviating to a greater or lesser degree from a direction perpendicular to the principal field. By these means the resultant magnetic vector will only be changed 40 as regards its direction and remains almost invariable as regards its absolute value.

In the accompanying drawings:

Figure 1 shows diagrammatically the directional relationship between two magnetic fields applied to a magnetron;

Figs. 2 to 4 inclusive show typical curves by which the principles of my invention are explained;

Figs. 5 and 6 show preferred arrangements of 55 the split anodes in a magnetron, and

Figs. 7 and 8 show respectively two different embodiments of my invention.

In Fig. 1 the vector H represents the main component of the magnetic field extending in the direction of the anode axis. Item Q is the vector of an auxiliary high frequency field for instance at a right angle to H . Item F is the effective field vector resulting from the two components and forming an angle α with the normal principal field H whereby the value of this angle depends upon the value of the cross field Q . The manner and reason for the angle α effecting a determining influence upon the oscillation performance will now be described.

As an example a magnetron will be considered 15 having cylindrically arranged plate segments and a single cathode in the axis of the anode cylinder. The principal magnetic field may extend approximately parallel to this axis. With a symmetrical structure and suitably chosen electrical and magnetic operating conditions it will be found that there is a dependence of the total emission current upon the angle α , as represented by curves in Fig. 2. In the working point X ($\alpha=0$; $Q=0$) on this curve the electron courses are level and most of 20 the electrons are just prevented from reaching the anode. Hence the falling off of the plate current.

In maintaining a working point Y and Y' respectively, a greater number of electrons arrives 30 at the anodes. This can be explained as follows:

There appears now besides the normal principal field H , a cross field causing the resultant field F to form a finite angle α with the axis of the anode cylinder. The electrons no longer 35 move in planes at right angles to the cathode, but wind themselves in a screw-like fashion about the turned resultant magnetic field as axis and thus reach the anodes without change in the value of the electrical or magnetic fields. Thus 40 if α is periodically varied for instance by superposing an alternating cross field crosswise to the principal field or by turning the electrode system relative to the direction of the field lines of the principal magnetic field, impulse-like current variations I_e are produced, and if the working point for rest is shifted to X , and if the variations of the angle towards positive or negative values of α are carried out approximately 45 up to the point in which the working points Y and Y' are reached, then the curves according to Fig. 3 will be obtained. In Fig. 3, there is plotted above the time t as abscissa axis, the angle variations $d\alpha=\pm\alpha$ and at the same time 50 the current impulses I_e are indicated. It can 55

be clearly seen that the emission current varies with the double frequency of the angle variations. The initial energy of the magnetron therefore has twice the frequency as compared with 5 the controlling high frequency cross field. In Fig. 4 the impulses I_e are shown in the same relation to t . However it is hereby assumed that the angular variations take place from a rest point Y and Y' respectively either in positive 10 values of α only or in negative values and approximately up to $\alpha=0$. The initial energy of the magnetron in this case has the same frequency as the controlling auxiliary cross field.

In the preceding discussion only the electron 15 physical actions within the discharge tube have been considered. For the exterior design of the circuit in accordance with the present invention there exists principally two different possibilities. On the one hand, the oscillatory circuit which 20 can be excited by the current impulses I_e can be placed directly between anode and cathode as shown in Fig. 7. Thus the two anodes are connected over the shortest possible distance and without interposing a resonant circuit. The 25 characteristics and mode of operation of the circuit arrangement shown in Fig. 7 will be set forth more in detail hereinafter.

A further possibility exists to operate the magnetron to be controlled with the ordinary symmetrical circuit in which the plate segments oscillate towards each other in at least two groups. Without the controlling cross field, oscillations 30 would be produced in this circuit by self-excitation and whose frequency would essentially depend upon the inductance L between the groups of anodes, upon the capacity of the partial anodes and upon an additional capacity C in parallel to the inductance. In adding a high frequency cross field to such a self-excited magnetron, the former acts as a choke valve for the 35 plate current in that it permits only such oscillations to assume high amplitudes whose frequency corresponds to the control frequency.

In this method a direct reaction of the controlled oscillations upon the controlling oscillation is impossible, since the flying electrons do not perform work at the controlling high frequency of the magnetic field. By integrating the product of the force times the distance,—

$$50 \quad \int K \cdot ds; K = H \cdot e \cdot v = 0$$

This is always true, since the force is at a right angle to the path.

55 H =magnetic vector
 e =charge of the electron
 v =velocity of the electron.

This fact will be readily understood, since a magnetic field can only produce a curvature in the path of the electrons but no variation in the 60 velocity. A magnetic field cannot change the kinetic energy, and neither supply the electron with work nor can it derive work therefrom.

Arrangements for putting into practice the idea of the invention are represented in the 65 Figs. 5 to 8 by way of example.

The magnetic cross field for varying the angle α can be produced in any desired way. According to Fig. 5 the anode segments A_1 and A_2 are disposed on one side of a looped conductor W_g , 70 while segments A_3 and A_4 are disposed on the other side thereof. The conductor W_g carries the control current and produces a magnetic field the axis of which passes through two of the slots, one intervening between the segments 75 A_1 and A_2 ; the other slot being between the seg-

ments A_3 and A_4 . The opposed anode segments A_1 and A_3 oscillate in 180° phase relationship. So, also, do the segments A_2 and A_4 . The cross field produced by the conductor W_g and acting upon the electron streams within the cylindrical 5 anode structure herein shown has been found to provide a very useful control of the oscillations.

In Fig. 6, the part of the cross field winding W_g extending parallel to the longitudinal axis of the anode segments is directly connected with the anode segments so that in practice these parts of the winding can be omitted. The anode segments are provided at one side with a connection strap B and at the other side with lead-in conductors Z for connecting to the control 10 oscillator.

Fig. 7 shows a magnetron circuit in which oscillation can be produced only when a control field is applied. In this embodiment there are but two anode segments A_1 and A_2 , which are 20 connected with each other by means of a short connection strap B . In the connection for the high frequency between anodes and cathode K an oscillatory circuit LC is inserted. This is tuned to a harmonic of the control frequency. 25 The electrical and magnetic characteristics are so chosen that the operating point is located at X on the curve $Y'Y$ as shown in Fig. 2. In this case anode current impulses of twice the control frequency are produced and they excite the oscillatory circuit LC .

The parallel connection LC may, if desired, be replaced by a series connection without departing from the spirit of the invention.

Fig. 8 shows a circuit in which the anodes A_1 and A_3 as well as A_2 and A_4 of a four part magnetron are joined respectively by two straps B . The groups of anodes formed in this way are likewise connected to each other across an oscillatory circuit L_1C_1 from which the produced high frequency 40 can be derived. In Fig. 8 the anodes A_2 and A_4 are connected to a source of control oscillations M across a Lecher wire line. The controlling source is suitably coupled to the Lecher system at such points that the voltage with respect to 45 the frequency produced is approximately equal to zero. The magnetron shown in Fig. 8 is capable as such of producing oscillations whose frequency is determined by L_1C_1 . This production of oscillations is, so to say, controlled by a separate source of control. A separately controlled magnetic cross field takes care that the oscillations undergo an amplitudinal increase to appropriate values only when the natural frequency of the circuit L_1C_1 conforms to the control frequency. The anodes A_2 and A_4 are identical as regards the oscillations to be controlled and they have the same potential at every instant. As regards the control frequency, the two anode segments are passed by currents in the opposite 50 sense. If necessary, the phase conditions between quasi self-excited oscillations and controlling oscillations can be corrected by values acting upon the duration of flow of the electrons. However, this will in general not be necessary, since a fixed 55 phase displacement does not cause disturbance.

I claim:

1. A generator of the magnetron type having an electron discharge tube said tube having a plurality of segmented cylindrical anodes and a centrally disposed linear cathode, in combination with means for producing a constant magnetic field in the region between the cathode and anodes, and means including a single conductive loop circuit 70 interposed between adjacent edges of said seg- 75

- mented anodes for introducing a magnetic cross field into the same region and at an angle to the lines of force of the constant magnetic field.
2. A generator of the magnetron type having an electron discharge tube, a set of at least four anode segments of cylindrical contour and a centrally disposed linear cathode within said tube, means for producing in said tube a constant magnetic field whose lines of force are substantially parallel to the electrode axis of the tube, means for conductively bridging two opposed anodes at corresponding ends thereof thereby to form these anodes into a conductive loop, and means for feeding high frequency current through said loop from the open ends thereof, thereby to cause said anodes to produce a transverse alternating magnetic field perpendicular to the electrode axis of said tube.
3. A circuit arrangement including a magnetron discharge tube having a centrally disposed linear cathode and a plurality of at least four anode segments of cylindrical formation co-axially surrounding said cathode, means for producing a constant magnetic field with its lines of force substantially parallel to the electrode axis, a conductive loop having two linear members disposed parallel to said cathode and on opposite sides thereof, and means for producing a magnetic cross field of alternating polarity in the region of the constant magnetic field, the last

said means being constituted by a source of alternating current fed to said conductive loop.

4. An oscillation generator comprising an electron discharge tube of the magnetron type, said tube having at least four cylindrically segmented anodes and a centrally disposed linear cathode, means for producing a magnetic field having its lines of force within the discharge zone of said tube substantially co-axial with the cathode and anodes, and further means including a circuit disposed between certain of said anodes and conductive of a high frequency alternating current for producing an auxiliary magnetic field within said discharge zone at an angle to the axis of said electrodes.

5. A device according to claim 4 and having the means for producing an auxiliary magnetic field inclusive of two of said segmented anodes.

6. A generator of the magnetron type having an electron discharge tube, a plurality of anode segments of cylindrical contour and a centrally disposed linear cathode within said tube, a conductive loop comprising two parallel members on opposite sides of said cathode and a bridging member interconnecting said parallel members at one end thereof, and means for feeding high frequency current through said loop from the open ends thereof and for producing a transverse alternating magnetic field at an angle to the electrode axis of said tube.
